CONTAINER SEALING MEANS

George T. Derby, Jacksonville, Fla.

Application June 13, 1942, Serial No. 446,916

9 Claims. (Cl. 215—37)

Generically this invention relates to a sealing means, but it more especially is directed to a jar or other container closure sealing means adapted to permit repeated use of the container.

One of the principal objects of this invention is the provision of a means for hermetically sealing the line of jointure between the body and closure of a jar or like container formed of glass, plastic, or other suitable material.

Another important object of this invention is the provision of a sealing means comprising a complementally formed recess in a container and top, a resilient element in said recess extending across the joint, and means in connection therewith for compressingly locking said element in sealing position.

A further important object of this invention is the provision of a container sealing means adapted to permit repeated use of the container and comprising a complementally formed recess in a container and closure, a resilient element adapted to overlie the joint and walls of said recess, and locking means coacting with said element to lock the latter in sealing position, said locking means being removable and replaceable.

With these and other objects in view, which will become apparent as the description proceeds, the invention resides in the construction, combination and arrangement of parts, herein-after more fully described and claimed, and illustrated in the accompanying drawing, in which like characters of reference indicate like parts throughout the several figures, of which:

Fig. 1 is a top plan view of a sealed container.

Fig. 2 is a section taken on the line 2—2 of Fig. 1.

Fig. 3 is a section taken on the line 3—3 of Fig. 1.

Fig. 4 is a view similar to Fig. 2 of a modified form.

Fig. 5 is a fragmentary perspective view of the removable locking means and resilient sealing element of Fig. 4 in disassembled relation.

The means for sealing glass and other like filled containers has been attended with more or less difficulty, usually requiring a sealing substance necessitating heating to effect the seal, and other sealing means often rendering it necessary to damage the top or cover thereby preventing repeated use of the container, and it was to overcome such deficiencies, and to provide a sealing means comprising a complementally formed portion in the meeting edges of the container and top forming, when the cover is in place, a recess adapted to receive a resilient element and means

in connection therewith for compressingly coacting with said element to effect the seal and maintain the same in sealing position, and admitting of easy removal, that I designed the sealing means forming the subject matter of this invention.

In the illustrated embodiment characterizing this invention there is shown a glass jar or container 1 formed adjacent to its upper edge with an interior rim or thickened portion 2 formed with a shoulder or lateral flange 3 on which is adapted to seat a glass top or closure 4, the exposed surface of which is in the same plane as the upper edge of the container.

Formed in the meeting edges of the container rim 2 and closure 4 are the complemental cut-out portions 5 and 6, respectively, each having a concave or curved wall portion 7, said complemental cut out portions forming, when the closure is operatively positioned, an annular recess 8 adapted to receive a rubber or gum gasket like sealing element 9 overlying the joint line 10 and extending to the upper edges of walls 7. Positioned in said recess 8 on the element 9 is a locking means 11 comprising the wire rings 12 and intermediate wedge wire ring or spreader member 13 formed with the ring receiving concave walls 14 adapted by the expansion of element 9 to maintain said rings and locking assembly in locked and locking position.

Said ring 13 is of a length so that its ends form a slight open space 15. One of said ends is undercut or beveled as at 16 and the other end vertical as at 17 which forms a fulcrum for the bar or the like 18 when inserted under the end 16 to effect removal of the locking means, as directly will more fully appear.

To apply the locking means and seal the container it is only necessary to place the resilient element 9 in recess 8 and then place the wires 12 on said element and the wedge-like wire 13 therebetween. The resilience of element 9 permits wire 13 to be forced down compressing element 9 against the bottom and side walls of recess 8 and tends to maintain the wires 12 in the ring 45 retaining concave seats 7 and 14, completely sealing the joint 10, and permits the removal of ring or spreader member 13 by a bar or other element 18, which releases the remaining rings and resilient element for ready removal. It will likewise be apparent that the above construction and coacting arrangement of parts, not only effects a removable sealing means, but also a container top or cover attaching and locking means, since when the wire or locking assembly is operatively mounted, the inwardly projecting edges of recess

8 constitute retaining or locking means, and prevent detachment or removal of the top. The container may be refilled and the sealing assembly replaced in sealing position, as in the first instance. It will thus be apparent that by virtue of my improved construction and sealing means, repeated use of the container is effected. Also, while, in the present instance, the container is constructed of glass, it, together with the components of the sealing means, may be constructed of suitable materials other than those herein described, such as composition materials, plastics, etc., without departing from the scope and spirit of the invention.

Fig. 4 illustrates a modified form of the invention embodying a somewhat simplified sealing means, comprising a container 1a formed with a rim or thickened portion 2a, having a lateral flange or shoulder 3a on which is adapted to seat a glass top or closure 4a, similar to the like features shown and described in connection with Figs. 1 to 3.

In the form illustrated in Fig. 4 the recess 8a is formed by the complementary cut out portions 5a and 6a, respectively, each formed with a curved wall surface 7a, and which together form the continuous curved wall surface of the recess 8a. Adapted to be positioned in the recess 8a is a rubber or other resilient sealing element 9a bridging or overlying the joint 10a. The resilient gasket or ring-like element 9a is normally, in cross sectional area, of the shape shown in Fig. 5, the thickened edge portions 19 being connected by a thin central portion or web 20.

The resilient sealing element 9a is positioned in the recess 8a similar to element 9. In this form the locking means comprises only one wire or other suitable ring 12a, which is similar in shape to ring 12, except that it is severed and its ends formed similar to ring 13, as at 16 and 17, and in operation it corresponds to ring 13 as an expanding and compressing locking means. In this form, when the element 9a is in place in the recess 8a, the ring 12a is placed on portion 20 of element 9a and when force is applied thereto in compressing direction the edges 18 are forced upwardly and said element assumes the shape and position shown in Fig. 4 with the ring 12a embedded therein in locked and locking position, completely sealing said container and securing the top thereon until manually removed, as will be clear from the preceding description.

From the above it will be apparent that I have designed a container structure and sealing means for effecting the sealing of containers effectively without requiring heat, sealing compounds, and the like, the sealing operation being easily and quickly accomplished, permitting ready and rapid removal of the sealing means and top, yet simple in construction, manufacturable at a negligible cost, and efficient for the purposes intended.

Although in practice it has been found that the form of the invention illustrated in the accompanying drawing and referred to in the above description as the preferred embodiment is the most efficient and practical, yet realizing that conditions concurrent with the adoption of the invention will necessarily vary, it is well to emphasize that various minor changes in details of construction, proportion and arrangement of parts, may be resorted to within the scope of the appended claims without departing from or sacrificing any of the principles of the invention.

Having thus described the invention, what is

desired protected by Letters Patent is as set forth in the following claims:

1. A locking and hermetically sealing assembly for a jar closure member comprising in combination a jar and a closure member supportingly seated within the jar, the meeting surfaces of the jar and closure formed with complementary cut-out portions having bottom and concaved side wall portions and forming a circumferential recess, said wall portions terminating in inwardly projecting spaced free retaining edges, a resilient sealing element in the recess and a locking ring assembly seating in said resilient element and expansively coating with said side walls and bottom to cause said element to assume the contour of and sealingly engage said side walls, retaining edges and bottom of the recess to lock said closure and hermetically seal the jar.

2. A locking and hermetically sealing assembly for a jar closure member comprising in combination a jar and a closure member in abutting relation supportingly seated therein, the abutting surfaces of the jar and closure being cut-out to form a circumferential recess having concaved side walls terminating in inwardly projecting free retaining edges, a resilient sealing element in the recess, and an annular locking means seating in and compressing said resilient element into the contour of and in sealing engagement with said side walls and edges to hermetically seal and lock the closure in the jar.

3. A locking and hermetically sealing assembly for a closure member within the neck of a jar comprising in combination the neck and a closure member in abutting relation supportingly seated therein, the abutting surfaces of the neck and closure member being formed with complementary cut-out portions to form a circumferential recess having arcuate walls terminating in inwardly extending free retaining edges, a sealing element of yieldable material within the recess, a locking ring means adapted to be pressed into conforming relation with said yieldable material causing it to assume the contour of and bindingly engage said walls and retaining edges to hermetically seal and lock the closure with respect to said jar.

4. A locking and hermetically sealing assembly for a closure member within the neck of a jar comprising in combination the neck and a closure member in abutting relation supportingly seated therein, the abutting surfaces of the neck and closure member being formed with complementary cut-out portions to form a circumferential recess having curved side walls with inwardly extending free retaining edges facing each other, a resilient member within the recess, an expandible annulus embedible in the resilient member, said annulus when expanded causing the member to assume the contour of and sealingly engage said side walls and edges to lock the closure and hermetically seal the jar.

5. A locking and hermetically sealing assembly for a closure member within the neck of a jar comprising in combination the neck and a closure member in abutting relation supportingly seated therein, the abutting surfaces of the neck and closure member being formed with complementary cut-out portions having spaced inwardly projecting free retaining edges and forming a circumferential recess having arcuate side walls, a sealing element of yieldable material within the recess, a ring means forced into the resilient material so as to pressingly spread it around said

means and the inner walls of the recess and when so pressed into sealing engagement with the latter said edges retaining said means against displacement, whereby locking of the closure and the hermetical sealing of the jar is effected.

6. A locking and hermetically sealing assembly for a closure member within the neck of a jar comprising in combination the neck and a closure member in abutting relation supportingly seated therein, the abutting surfaces of the neck and closure member being formed with complementary cut-out portions to form a circumferential recess having arcuate side walls terminating in inwardly projecting spaced retaining edges, a resilient sealing member in said recess, an annulus embedible in the resilient member to compress the member until it assumes the contour of and sealing engagement with the side walls of said recess, the annulus being retained in its embedded position against displacement by the enveloping resilient material and edges to lock the closure and hermetically seal the jar.

7. A locking and hermetically sealing assembly for a closure member within the neck of a jar comprising in combination the neck and a closure member in abutting relation supportingly seated therein, the abutting surfaces of the neck and closure member being formed with complementary cut-out portions to form a circumferential recess having arcuate side walls, a sealing element of yieldable material in said recess, a pair of rings and an intermediate spreader member wedged between the rings, the wedging action of the spreader member separating the rings and causing them to compress the resilient material until it assumes the contour of and sealing engagement with the side walls of said recess to lock the closure and hermetically seal the jar.

8. A locking and hermetically sealing assembly for a closure member within the neck of a jar comprising in combination the neck and a

closure member in abutting relation supportingly seated therein, the abutting surfaces of the neck and closure member being formed with complementary cut-out portions to form a circumferential recess having arcuate side walls, a resilient member in said recess, a ring assembly comprising a pair of rings and an intermediate spreader member wedged between the rings, the wedging action of the spreader member separating the rings and

10 causing them to compress the resilient member until it assumes the contour of and sealingly engages the inner wall surfaces of the recess, the expansive qualities of said resilient member maintaining said assembly in locking position to lock the closure and hermetically seal the jar, and means in connection with said spreader member to effect its disengagement from said rings.

9. A locking and hermetically sealing assembly for a closure member within the neck of a jar 20 comprising in combination the neck and a closure member in abutting relation supportingly seated therein, the abutting surfaces of the neck and closure member being formed with complementary cut-out portions to form a circumferential recess having arcuate side walls, a sealing element of yieldable material in said recess, a ring assembly comprising a pair of rings and an intermediate spreader member wedged between the rings and having its opposite side walls 25 conforming to the contour of the contacting surfaces of said rings, the wedging action of said spreader member forcing the rings in opposite directions and causing them to compress the resilient material until it assumes the contour of and sealing engagement with the side walls of said recess, the inherent expansion of said resilient material maintaining said assembly in locking position to lock the closure, and hermetically seal the jar, and means in connection 30 with said spreader member to effect its removal.

GEORGE T. DERBY.
